UNITED STATES PATENT OFFICE.

JOHN H. COBB, OF FAIRFIELD, CONNECTICUT.

SASH-FASTENER.

1,312,893.

Specification of Letters Patent.

Patented Aug. 12, 1919.

Application filed April 10, 1919. Serial No. 289,035.

To all whom it may concern:

Be it known that I, JOHN H. COBB, a citizen of the United States, residing at the town of Fairfield, in the county of Fairfield 5 and State of Connecticut, have invented certain new and useful Improvements in Sash-Fasteners; and I do declare the following to be a full, clear, and exact description of the invention, such as will enable others 10 skilled in the art to which it appertains to make and use the same.

This invention relates to certain new and useful improvements in window fasteners, and the primary object of the invention is to 15 provide a fastener of this type which is of simple and economical construction, and which can be easily and quickly operated and which has simple and novel means for holding the parts in positive locked position.

The invention relates to the type of window fastener in which both sashes are locked either in closed position, or in various open positions, and further aims to provide means which is of novel construction 25 involving a minimum of parts.

In the drawings:

Figure 1, is a sectional view showing the invention applied to the sashes and in locked 30 position;

Fig. 2, is a top plan view with the cover plate removed, showing the parts in retracted position; and

Fig. 3, is a section on line 3—3 of Fig. 1. 35 In proceeding in accordance with the present invention, a casing is employed having a base plate 1, formed with cut-out portions to provide a guide for a sliding locking bolt or member 2, and a curved pivoted locking bolt or member 3, the latter being tensioned by a spring 4, and resting in retracted position on or against a seat 5, formed on the base plate. The sliding bolt 2, has an enlarged inner end portion 6,

45 formed with a cam face 7, disposed at an incline as shown, the cam face being for engagement with the curved rear edge of the pivoted bolt 3, for a purpose shortly to be set forth. A lug 8, is formed on the 50 sliding bolt 2, and projects upwardly therefrom, and is adapted to be received in either of two apertures 9, formed in a latching plate 10, which latter is hinged at 11, to a cover plate or closure 12, the cover plate 55 having a cut-out in which the flap or plate 10, is pivoted, so that as shown in Fig. 3,

the plate 10, will rest directly on top of the sliding bolt 6, and receive the lug 8, of the latter in one of its two openings 9. The plate 10, is preferably formed with a 60 depending finger grip 10', so as to permit of easy manipulation thereof.

As shown in Figs. 1 and 2, the casing has a cut-out 13, which is for the purpose of receiving the sash cord 14, the device being 65 screwed to the top of the lower sash close to the upper sash as depicted in Fig. 1, while the window casing is formed with a series of vertical spaced openings 14', for receiving the sliding bolt, and the side rail 70 of the upper sash is formed with a like series of openings 15, to receive the pivoted bolt 3.

In operation, the flap or plate 10, is lifted, and the lug 8, gripped to throw the bolts to either locked or unlocked positions, the two 75 bolts moving in unison due to the cam face 7, which acts to move the pivoted bolt outwardly, and the spring 4, which acts to move the bolt 3, inwardly upon retraction of the support afforded by the cam face 7, 80 following which the flap 10, is moved downwardly to reengage the lug 8, and lock or latch the two bolts. The openings 9, are spaced at such distance apart so that in one position of the parts one opening will receive 85 lug 8, to hold the parts locked and in another position of the parts will receive the lug 8, in the other opening to hold the parts inoperative.

It will be apparent from the foregoing 90 that the device involves a minimum of parts which are not likely to become out of order and that a simple and easily operated lock is afforded by the mere swinging of the flap 10, to hold the parts positively in operative or inoperative positions, the movement of the two bolts in unison being easily and quickly effected by mere sliding of bolt 2, upon gripping of or through the medium of the lug 8.

100 What is claimed is:

1. In a window fastener, a casing composed of a base plate formed with a cut-out to form a curved seat, a sliding bolt in the cut-out having an enlarged rear end formed 105 with an inclined cam face, a lug projecting upwardly from the bolt, a curved pivoted bolt in the cut-out resting in one position against the seat, a spring for tensioning the pivoted bolt to normally hold same within 110 the cut-out, a cover plate for the casing having a cut-out, a plate hinged to the cover

plate and operating in the cut-out of the latter and formed with a plurality of spaced openings to receive the lug in different positions of the sliding bolt, and said casing 5 being formed with a cut-out in an end thereof to receive the sash cord, and being formed for securement to the upper rail of the lower sash.

2. In a window fastener, a casing having 10 a cover, the latter formed with a cut-out, a plate hinged to the casing and operating in the cut-out of the cover and formed with a pair of spaced openings, a sliding bolt in the casing having a lug receivable in 15 either of the hinged plate openings, a pivoted bolt in the casing operated by the outward movement of the sliding bolt, and means to tension the pivoted bolt so as to move same into the casing upon retraction 20 of the sliding bolt.

3. In a window fastener, a casing formed

with ways and mortises, a sliding bolt and a pivoted bolt within said ways and mortises, the sliding bolt during its projection acting against the pivoted bolt to swing the 25 latter to locking position, and a spring for withdrawing the pivoted bolt from locking position when the sliding bolt is retracted.

4. In a window fastener, a casing, a sliding bolt in the casing having an enlarged 30 contact portion, a pivoted bolt in the casing having its bottom part in contact with said portion, whereby when the sliding bolt is projected the pivoted bolt will be swung to locking position, and spring means which 35 always acts against the pivoted bolt to return it to unlocked position.

In testimony whereof I affix my signature.
JOHN H. COBB.
